UNITED STATES PATENT OFFICE.

EDWARD P. FOLGER, OF BOUND BROOK, NEW JERSEY.

SMOKE AND GAS RETURNING MEANS FOR STOVES AND FURNACES.

1,150,934.

Specification of Letters Patent. Patented Aug. 24, 1915.

Application filed February 26, 1912. Serial No. 679,823.

To all whom it may concern:

Be it known that I, EDWARD P. FOLGER, a citizen of the United States, residing at Boundbrook, in the county of Somerset and State of New Jersey, have invented certain new and useful Improvements in Smoke and Gas Returning Means for Stoves and Furnaces, of which the following is a specification.

10 My invention relates to new and useful improvements in means for returning the products of combustion, including smoke and gases, from a stove or furnace after they have left the combustion chamber to a 15 point where they may be delivered to the combustion chamber to be consumed, the invention contemplating means whereby the smoke and gases may continuously circulate through the combustion chamber whereby 20 the total or maximum fuel efficiency is attained.

The invention consists in the construction and arrangement of parts to be fully described hereinafter, and the novelty of which 25 will be particularly pointed out and distinctly claimed.

I have fully and clearly illustrated my invention in the accompanying drawings to be taken as a part of this specification and 30 wherein:

Figure 1 is a view in elevation taken in longitudinal section of a structure embodying my invention adapted for use as part of the exit flue of a stove or furnace; Fig. 2 is a similar view of another embodiment of 35 the same invention; Fig. 3 is a view in vertical longitudinal section of a stove or furnace in which is incorporated a structure exemplifying my invention; Fig. 4 is a longitudinal section through a flue having one 40 form of my invention applied thereto; Fig. 5 is a vertical longitudinal section through a structure embodying my invention adapted 45 to be interposed in a flue pipe of a stove or furnace.

Referring to the drawings by characters of reference, 1 designates a flue pipe leading from a stove or furnace, the same being shown as vertically disposed and having an 50 open upper end therein. This flue, at its upper end portion, enters the bottom plate 3 of a casing which, although not necessarily, may be formed by a frusto-conical wall 4 closed at its upper end by a top wall 5 having a central opening 6 in which is sealed in any suitable manner the lower end

of a continuation 7 of the flue pipe, the continuation forming the outlet for smoke and gases from said casing. In this construction the casing 4 connects the flue sections 1 and 5 7 so that the products of combustion passing up through the flue 1 will pass through the chamber 4 to the flue section 7 and said casing practically forms part of the flue. 10

As shown in the drawings, the upper end 65 of the flue pipe 1 projects for a distance within the chamber 4 above the bottom plate 3, as shown at 8, the projecting portion 8 being provided with an outwardly-flaring flange 9. Supported by this projecting portion 8 of the flue 1 are spider arms 10, upon the outer end portions of which is supported the lower open end of a chamber 11 which 70 may be substantially cone-shaped and of such diameter as to leave an annular space 12 between its wall and the wall of the chamber 4, so that the products of combustion may flow from the pipe 1 into said chamber and down beneath its lower edge and up through the annular space 12 to the 75 flue section 7. The upper end of the chamber 11 is closed and terminates short of the top wall 5 of the chamber 4 and is provided with a central opening 13 through which 80 opens a collecting chamber preferably in the form of a conduit 14, said conduit extending longitudinally through the chamber 11 and the upper portion of the flue section 1. The lower end of the conduit is connected to an imperforate inlet pipe 14^a which is 85 directed laterally and projected through an opening 15 in the side wall of said flue 1, the inlet end of said pipe being external of the flue. The upper end of the collecting 90 conduit 14 is connected to and communicates with a return pipe section 16 which is directed laterally through an opening 17 in the side wall of the chamber 4, and then downward, said return pipe 16 being adapted to be connected with the stove or furnace 95 in connection with which the device is used, preferably beneath the grate. The collecting conduit 14 is provided with suitable inlets whereby products of combustion entering the chamber 11 may, under circumstances to be hereinafter set forth, enter said 100 collecting conduit 14. The inlets just mentioned may take any suitable form, but I preferably make them in the form of slits 19 extending longitudinally of said collecting conduit 14, substantially as shown in 105 Fig. 1 of the drawings. The outer lower

110

end 15^a of the collecting conduit 14 is provided with any suitable damper 18 by means of which said conduit may be opened or closed.

5 The pipe section 7 is preferably provided with any form of a damper, such, for instance, as the well-known type of pivoted damper 20, by means of which communication between said pipe and the chamber 4 10 may be established or cut off. I may also, if desired, although it is not essential, interpose in the return conduit 16 a blower or exhauster 21 of any suitable type to increase the draft through said pipe.

15 The parts being as just described, the operation is as follows: If it is not desired that the products of combustion be returned to the stove or furnace to be consumed therein, the damper 18 is closed and the 20 damper 20 is moved to position to establish communication between the chamber 4 and the flue section 7, so that the products of combustion, passing up through the flue 1, will enter the chamber 11 and then flow 25 down under the lower edge of the latter, thence up through the space 12 and the upper end of the chamber 4, whence they flow out through the flue section 7. Under the 30 conditions just described, the collecting conduit 14 and the return pipe 16 perform no function, all the products of combustion passing freely from the furnace through the flue 1 and the chambers 11 and 4 to the flue outlet 7.

35 Should it be desired to return the products of combustion to the furnace or stove, the damper 18 is moved to open the lower end 15^a of the collecting conduit 14 to the outer atmosphere, and the damper 20 is operated to cut off communication between the chamber 4 and the flue section 7. Under 40 these conditions, the draft in the stove or furnace, to which the return section 16 is connected, will cause cold air to flow into the open end 15^a of the collecting conduit, and thence upward through said conduit into the return pipe section 16. This circulation of the cold air into the collecting conduit tends to create a vacuum therein which 45 results in the products of combustion being drawn into the conduit through the slits 19, from which conduit they pass through the return pipe 16 to the stove or furnace. The circulation is also effected in part by the fact 50 that the return pipe and the gases therein are of a lower temperature than the heated products delivered into the collector chamber. During this last operation the exhauster or blower 21 may be operated or not, 55 accordingly as to whether or not sufficient circulation is created by the natural draft of the stove and the inflow of the cold air to the collecting conduit. The primary cause of the circulation is the fact that the 60 cold air flowing into the collecting conduit 65

in the presence of the highly heated gases in the chamber 11 causes a contraction of the gas in said conduit sufficient to draw the highly heated gases into the conduit 14 so that they may flow therethrough and through the return pipe 16 to the furnace, and being further assisted in their flow because of lower temperature in the return pipe.

70 In Fig. 2 a somewhat modified structure is shown from that of Fig. 1, the upper end of the inner chamber 11 being closed by the upper wall 22 of the casing 23, which is the equivalent of the chamber 4, heretofore described, except that it is made substantially 75 cylindrical instead of conical. In this form of the invention the collecting conduit 14 is connected with the return pipe section 16 through the upper end of the chamber 23, and said chamber has its connection with 80 the outlet flue through its upper wall at a point eccentric to the point at which the return pipe connects with the collecting conduit, the flue outlet being shown at 24. The operation of this form of the invention is 85 substantially identical with that heretofore described, and it is not believed necessary to repeat the description of that operation here. This form of the invention is particularly 90 adapted for use in situations where the 95 length of a vertically extending flue between the furnace or stove and the point where it leaves the apartment would not permit of the use of the form shown in Fig. 1.

95 In Fig. 3 the invention is shown as forming part of the structure of a stove or furnace which may be of any suitable type, the same being shown as consisting of a shell 24 provided with a grate 25 and a partition 26 separating the shell into the combustion 100 chamber 27 and a circulation chamber 28. In this form of the invention an outlet conduit or flue 29 extends through an opening in the partition 26 to establish communication between the chambers 27 and 28, said flue 29 supporting a spider 30 at a distance 105 above the partition 26, upon the outer end of which spider is supported a cone chamber 31, the upper end of which abuts and is closed by the upper wall 32 of the stove or 110 furnace shell. Extending longitudinally through the cone shell centrally thereof is a collecting conduit 33, the lower end of which is connected to a pipe section 34 extending 115 down through the flue 29 into the combustion chamber, and thence laterally out through an opening 35 in the shell of the stove or furnace, so that cold air exterior to the stove or furnace may be admitted to the conduit 33, the outer end of the pipe section 34 being controlled by a damper 36.

120 The upper end of the conduit 33 is connected to a return pipe section 37 which is directed laterally, exterior of the stove, and thence downward, where it is connected to 130

and opens through a stove shell beneath the grate, as shown at 38. The chamber 28 opens into an outlet flue 39 which is controlled by a damper 40 to establish and cut off communication between said flue and the chamber 28. It is believed that the operation of this arrangement will be apparent, but it may be briefly stated as follows: When the natural circulation of the stove 5 is to be maintained the damper 36 is moved to closed position and the damper 40 to open position, so that the products of combustion pass from the combustion chamber 27 up through the flue 29 into the chamber 10 31, thence from the chamber 31 to the chamber 28, from which they emerge through the flue 29, which, it will be understood, 15 communicates with a chimney or stack. If the products of combustion are to be returned 20 to the furnace for consumption, the damper 36 is opened and the damper 40 moved to closed position, so that the cold air entering the pipe 34 flows into the conduit 33. This presence of the cold air in said collecting 25 conduit, as heretofore set forth, causes a contraction of the gas therein, resulting in the heated products of combustion being drawn into said conduit, from which they pass to the return pipe 37 and are delivered 30 to the interior of the stove or furnace beneath the grate.

In the simplified form shown in Fig. 4, 41 indicates a flue controlled by a pivoted damper 42 within which, and extending 35 longitudinally thereof, is a collecting conduit 43 provided with longitudinal inlet slits 44, permitting ingress of products of combustion within the flue 41 under circumstances to be presently set forth. The upper 40 end of the conduit 44 is connected to the return pipe 45, which extends exterior of the flue and is adapted to have its lower end connected to the stove in the same manner as the other forms heretofore described. 45 The lower end of the conduit 44 is connected to a pipe section 46, which extends exterior of the flue, as at 47, and is provided with a controlling damper 48. When the stove draft is to operate in the usual manner, the damper 48 is closed and the damper 42 is opened so that the products of combustion pass through the flue without the return device operating, but, when it is desired 50 to return the smoke and gases to the stove or furnace the damper 42 is closed and the damper 48 opened so that the cold air may pass through the conduit 44. This causes the products to enter the said collecting chamber 44, whence they pass through the 55 return pipe 45 to the furnace or stove. In this form of the invention the flue constitutes a casing for the collecting conduit.

The form shown in Fig. 5 is substantially the same as that illustrated in Fig. 1, except 60 that the inner cone chamber is formed with

inner and outer spaced concentric walls 50, 51, respectively, forming an annular space 52 closed at its lower end by a wall 53. The space between these walls communicates with a return pipe 54 leading to the furnace or stove. The cone chamber is closed at its upper end by a wall 55. The collecting conduit 56, which may be of the same form as heretofore described in the other forms of the invention, is shown at 56 and 70 extends longitudinally and centrally through the inner cone 50, said conduit communicating at its upper end through the upper end of said cone 50 with the space 52, and at its lower end having an imperforate inlet extension 57 extending down through the flue 58 to a point exterior thereof, the outer end being controlled by a damper 59. The damper 60 is also used to control communication between the outlet flue section and the 75 outer chamber, in which the collection conduit and cone chamber are arranged. It is thought that the operation of this form of the invention will be obvious taking into consideration the description of the operation of the forms heretofore described. 80

Such final products of combustion as are not consumed by the fire due to the circulation described, pass from the system, part being carried off through the outlet stack or 95 flue constituting the outlet when the consumer is not working, and part being carried by the return pipe to the base of the stove or furnace. This disposition of the final products takes place in each of the embodiments shown and described. 100

It will be understood that the damper in the outlet flues or stacks may be of the usual type which permits passage of a limited part of the products even when set to cut 105 off the draft. It will also be understood that when the invention is in operation the increased supply of air and the circulation thereof increases the combustion so that the products are reduced to such a degree as to 110 be effectively eliminated in the manner above described.

What I claim and desire to secure by Letters Patent of the United States is:—

1. In a device of the character described, 115 a flue, a perforated collector chamber extending through said flue and in communication with the said flue, said chamber being connected at its upper end to a return conduit opening through the wall of the flue 120 and extending exteriorly of the flue and adapted to be connected to a stove or furnace, and an air inlet pipe connected to the lower end of said collector chamber and communicating therewith, and having an 125 inlet externally of the flue.

2. In a device of the character described, 130 a flue, a collector chamber consisting of a perforated pipe section extending through said flue, an imperforate pipe section con-

- 5 nected to the lower end of said chamber and having an inlet externally of the flue, and an imperforate return-pipe section connected to the upper end of said collector 10 chamber and extending externally of the flue and adapted to be connected to a stove or furnace.
- 15 3. In a device of the character described, a casing having a flue inlet and outlet, a chamber in said casing into which said flue inlet opens, and communicating with the casing, a perforated collector chamber in said first-named chamber, and having an inlet externally of said casing, and a return 20 conduit connected to the said collector chamber and extending externally of the casing.
- 25 4. In a device of the character described, a casing, a flue projecting into the base of the casing, a damper controlled outlet from the casing, a chamber in the casing spaced therefrom, and in communication therewith and into which the inlet flue opens, a perforated collector chamber in said first-named 30 chamber, a return conduit connected to said collector chamber and extending externally of the casing, and an inlet conduit connected to the collector chamber and having an inlet opening externally of said casing.
- 35 5. In a device of the character described a casing having a flue inlet and outlet, a chamber in the casing spaced therefrom and having an open bottom, means for supporting the chamber with its open bottom above the base of the casing and over the flue inlet, a perforated collector chamber within said first-named chamber and having an inlet conduit connected to its lower end, and opening externally of the casing, and a return conduit connected to the upper end of the collector chamber and extending externally of the 40 casing.
- 45 6. In a device of the character described, a casing having a flue inlet and outlet, a chamber in the casing spaced therefrom and having an open bottom, means for supporting the chamber with its open bottom above the base of the casing and over the flue inlet, a perforated collector chamber within said first-named chamber and having an inlet conduit connected to its lower end, and opening externally of the casing, a return conduit connected to the upper end of the collector chamber and extending externally of the casing and adapted to be connected to a stove or furnace, and dampers 50 for controlling said inlet conduit and outlet flue.
- 55 7. In a device of the character described, in combination, a casing having a flue inlet and a damper-controlled outlet, a chamber supported within the casing and spaced therefrom and having an open lower end spaced above the base of the casing to provide communication between said chamber and casing and said chamber having a closed upper end, a perforated collector chamber arranged in said first-named chamber, a return pipe connected to the upper end 60 of said collector chamber and extending externally of the casing, and an inlet pipe connected to the lower end of said collector chamber and extending externally of the flue and casing.
- 75 In testimony whereof I have hereunto signed my name in the presence of two subscribing witnesses.
